UNITED STATES PATENT OFFICE

SAMUEL NOEL CHEW, OF THORNTON HEATH, ENGLAND

GAS AND AIR WASHING APPARATUS

Application filed June 6, 1927, Serial No. 186,969, and in Great Britain June 10, 1926.

This invention relates to gas and air washing apparatus and has for its object to provide an improved apparatus particularly adapted for use in connection with pneumatic 5 conveyance and extraction for finally relieving the air of impurities before it reaches the prime mover, the latter being usually a rotary or reciprocating exhauster.

According to this invention, the washer 10 comprises a tank or container part filled with water or other suitable liquid through which the air passes in a horizontal direction at a relatively slow speed, the air passing beneath a screen consisting of a series of baffles attached to wood or other float bars secured to a backing or sheet of canvas or other suitable flexible material, the baffles being arranged to form a tortuous path or paths for the air.

Upon the accompanying drawings:—
20 Fig. 1 is a longitudinal sectional elevation.
Fig. 2 a part sectional end elevation, and

Fig. 3 a part plan of the improved air washing apparatus.

Figs. 4 and 5 are plan views of two of the 25 transverse float bars showing the arrangement of the baffles.

The apparatus comprises a sheet metal outer casing *a* with tapered air inlet conduit *b* at one end and tapered outlet conduit *c* at 30 the other end. Enclosing the upper part of the casing between the inlet and outlet conduits is a removable cover *d*. The bottom *e* of the casing slopes away to a sludge valve *f* and provides a space in which the sludge can 35 settle. Within the casing and extending from inlet to outlet, and the full width of the casing, is the flexible backing or sheet *g* preferably made of tarpaulin, and secured by its edges to the sides of the casing by strips of 40 angle iron *h*, the sheet being transversely pleated at *g* at intervals, and completely sealing the upper part of the casing. Secured to the underside of the sheeting *g* are 45 transverse wood bars *i* lying between the pleats *g* and each carrying two sets of depending sheet metal baffle plates *j*, the lower ends of the baffles in each set being connected by a transverse rod *j*, the ends of which underlie fixed locating angle bars *k* on the sides 50 of the casing, see Fig. 2. Each transverse

bar is suspended by eye bolts *l* from hook bolts *l* passing through transverse angle bars *m* the adjustment of the bolts *l* being such as to allow a small rocking movement of the transverse bars *i*.

On the inlet side of the casing *a* is an adjustable baffle plate *b* extending down into the water and under which the air to be washed is drawn.

Around the lower end of the casing *a* is a 60 perforated pipe *o* for filling the apparatus with water and for flushing the inclined sides of the bottom when removing the sludge.

As shown in Figs. 4 and 5, each bar *i* is provided with one set of three baffle plates and 65 one set of four baffle plates in staggered relationship, in order to interrupt the straight-through passage of the air. The baffles are preferably relatively rigid so that they move together with the rocking of the transverse 70 bar.

The sheet *g* always lies below the level of the water in the casing.

In use, the air having completed its work and being laden or charged with dust or other matter, is led through pipe *b* which pipe increases gradually in area towards the washer, so as to reduce the air speed to the required degree to prevent undue agitation in the washer. The air on entering the washer 80 passes under the adjustable plate *b* and under the flexible backing or sheet *g* and in the paths formed by the baffles *j* and in doing so impinges on the wet surfaces of the baffles and of the transverse bars and flexible backing or sheet, which surfaces break up air bubbles and ensure complete cleansing of the air. The constant agitation in the tank caused by the passage of the air ensures constant flushing of the underside of the float 90 bars and of the sides of the baffles *j*, thus preventing any deposition of sludge, etc., thereon, and providing the desirable wet surface. The air passes from the washer into the further tapering pipe *c* which reduces the size of 95 the air passage to suitable dimensions for connection to the prime mover.

In passing between the baffles, the air causes a rocking or oscillation of the float bars and baffles, which assists the breaking up of 100

the air bubbles and separation of the dust, etc. from the air.

The pleats give freedom of movement of the float bars and baffles.

5. What I claim is:

1. In gas or air washers comprising a closed container partly filled with a liquid through which the gas or air passes, a sheet of flexible material in the container below the level of the liquid, a passage for the gas or air below such sheet, an inlet and outlet for the gas or air to such passage, which is otherwise closed, a series of transverse float bars secured to said sheet and baffles in said passage depending from the said float bars, to interrupt the straight-through passage of the gas or air, having a freedom of movement, as set forth.

2. In gas or air washers comprising a closed container partly filled with a liquid through which the gas or air passes, a sheet of flexible material in the container below the level of the liquid, a passage for the air or gas below such sheet, an inlet and outlet for the gas or air to such passage, which is otherwise closed, a series of transverse float bars secured to said sheet, sets of relatively rigid depending baffles secured to said float bars, a longitudinal locating bar on each side of and inside the container, transverse rods connecting the lower ends of the baffles in each set, and projecting beyond such baffles to engage below said locating bars, the baffles in adjacent sets being arranged in staggered relationship, and supports for the float bars allowing the baffles a small swinging movement, as set forth.

3. In gas or air washers comprising a closed container partly filled with a liquid through which the gas or air passes, a sheet of flexible material in the container below the level of the liquid, a passage for the gas or air below such sheet, an inlet and outlet for the air or gas to such passage, which is otherwise closed, a series of transverse float bars secured to said sheet, baffles in the said passage depending from the float bars, to interrupt the straight-through passage of gas or air, having a freedom of movement, and an adjustable depending baffle plate at the inlet to said passage, as set forth.

4. In gas or air washers comprising a container partly filled with a liquid through which the gas or air passes, a sheet of flexible material in the container below the level of the liquid, a passage for the air or gas below such sheet, an inlet and outlet for the gas or air to such passage, which is otherwise closed, a series of transverse float bars secured to said sheet, sets of relatively rigid depending baffles secured to said float bars, a longitudinal locating bar on each side of and inside the container, transverse rods connecting the lower ends of the baffles in each set and projecting beyond such baffles to engage below said locating bars, the baffles in adjacent sets being arranged in staggered relationship, supports for

the float bars allowing the baffles a small swinging movement, and an adjustable depending baffle plate at the inlet to said passage, as set forth.

5. In gas or air washers comprising a closed container partly filled with a liquid through which the gas or air passes, a flexible tarpaulin sheet in the container below the level of the liquid, having a plurality of transverse pleats at intervals, a passage for the gas or air below such sheet, an inlet and outlet for the gas or air to such passage, which is otherwise closed, a series of transverse float bars secured to said sheet between the said pleats, and baffles in said passage depending from the said float bars, to interrupt the straight-through passage of the gas or air, having a freedom of movement, as set forth.

6. In gas or air washers comprising a container partly filled with a liquid through which the gas or air passes, a flexible tarpaulin sheet in the container below the level of the liquid, having a plurality of transverse pleats at intervals, a passage for the gas or air below such sheet, and inlet and outlet for the gas or air to such passage, which is otherwise closed, a series of transverse float bars secured to said sheet between the pleats, sets of relatively rigid depending baffles secured to said float bars, a longitudinal locating bar on each side of and inside the container, transverse rods connecting the lower ends of the baffles in each set and projecting beyond such baffles to engage below said locating bars, the baffles in adjacent sets being arranged in staggered relationship, and adjustable suspension supports for the float bars allowing the baffles a small swinging movement, as set forth.

7. In gas or air washers according to claim 2, adjustable suspension supports for the float bars, as set forth.

In testimony whereof I have signed my name to this specification.

SAMUEL NOEL CHEW.
